ELECTRON-DISCHARGE DEVICE

Application filed January 20, 1926, Serial No. 82,581, and in Great Britain January 24, 1925.

This invention relates to electron discharge devices such as thermionic valves used in the art of wireless telegraphy and telephony and has particular reference to the 5 so-called "soft" type of such devices, that is to say those in which ionization plays a material part in determining the characteristics of the device.

The primary object of this invention is to 10 amplify or otherwise improve the negative resistance or impedance characteristics of such electron discharge devices. Further objects will transpire hereinafter.

According to this invention an ionic 15 charge collector of extended surface is employed, such collector being the electron controlling member or an element associated with it so disposed that there are communicated to such collector charges having a component in phase with the charges on the electron controlling member which gave rise to 20 the change in the ionization within the tube.

This invention may be stated to consist of a device comprising a cathode, an anode, 25 a further electrode or electrodes and a medium capable of ionization at a pressure sufficient to give the device negative resistance or impedance characteristics of a type which are smoothly and easily controllable over a wide range of values while the value of the 30 negative resistance or impedance is sufficiently low to give zero decrement to circuits having values of L, C and R commonly employed in radio circuits. Such negative impedance characteristics are in part maintained at frequencies exceeding 10^6 cycles 35 per second and the apparatus when suitably adjusted will operate as a rectifier or detector of electrical oscillations applied to it, or it may be employed for the amplification 40 of oscillations or other electrical variations. Alternatively, it may operate simultaneously as a negative impedance device and as a detector or as an amplifier or both as a detector and amplifier. Further features of 45 the invention will be described in the following specification.

Electron discharge devices containing 50 traces of gas or vapour sufficient in amount to affect appreciably the electrical perform-

ance of the device, show under suitable conditions of adjustment, a falling grid-current grid-voltage characteristic but the numerical value expressed in ohms of the negative impedance which this falling characteristic indicates is usually much too large to be of practical utility at any rate in circuits having convenient values of L, C and R. In order to develop an appreciable slope in such grid characteristics abnormally high anode 55 voltages have sometimes been employed. Furthermore, the development of a negative slope in the static grid characteristic, when plotted point by point by the ordinary methods of observation, is no guarantee that such 60 a device will operate to reduce appreciably the decrement of an associated circuit tuned to the higher radio frequencies.

The desired characteristics are obtained 65 according to the present invention by the use of an electrode or electrodes of extended surface so proportioned or disposed as to receive the charges of the positive ions formed from the contained gas or vapour by the passage of the electron discharge. Such 70 electrode or electrodes is or are arranged so as to present a surface substantially parallel to or out of the electron stream, large compared with that in or transverse to the electron stream. This result may be attained by 75 suitably proportioning or disposing the electrode or by both means. In some cases it is advantageous to extend such collectors of 80 ionic charges into the zones of richest ionization.

In order to reduce as far as possible any time-lag effect that might become apparent at high frequencies, it is preferred to employ gas of small molecular weight in the envelope although it seems probable that at 85 the highest frequencies it is chiefly those ions formed from molecules near the collector, or possibly in contact with it, which are usefully engaged in the operation of the device. On account, therefore, of its low 90 molecular weight and well known stability of pressure at moderate potentials, it is preferable to employ helium as the medium 95 through which the electron discharge passes although other gases or vapours may be used. 100

Experiments have shown, however, that on comparing two electron discharge devices of similar construction and dimensions one filled with a mixture containing about 95% helium and 5% neon with possibly traces of other gases and the other containing approximately 80% neon and 20% helium with possibly traces of impurities and adjusting the devices for equal negative impedances at a frequency of 10^6 cycles that the static characteristic of the neon filled device was more than twice as steep as that of the helium filled device. That is to say, the performance at 10^6 cycles of the device containing chiefly neon had fallen off much more from its static characteristic than had that of the device containing chiefly helium. The anode voltages employed during the experiments were the same and the radio-frequency impedances were adjusted by controlling the filament currents. The total pressure in the helium filled tube was greater than that in the neon filled tube. It is assumed that the ratio of charge to mass for most of the ions taking a useful part in the production of the radio-frequency negative impedance slope, is smaller in the case of the valve containing chiefly neon than in the case of that containing chiefly helium. It should be noted, however, that further investigation may modify this theory. It is possible that in taking the static characteristics, the emission from the filament is influenced from point to point by differences produced by its ionic or molecular bombardment by molecules of different mass and velocity.

Several embodiments of the invention will now be described with reference to the accompanying drawings in which:

40 Figures 1 and 2 represent diagrammatically a cross section and elevation respectively of one form of construction.

45 Figures 3 and 4 show series of characteristic curves for a device constructed in accordance with Figures 1 and 2.

Figures 5, 6 and 7 illustrate modified forms of construction.

Figure 8 illustrates a radio circuit incorporating the invention.

50 Fig. 9 is an elevational view of a complete valve employing the construction of Fig. 7.

Figure 10 illustrates a form of the invention in which the grid is composed of flat plates;

55 Figure 11 is a vertical sectional view of the form of the invention shown in Fig. 6 having an external coil adapted to establish a magnetic field within the tube; and

60 Figure 12 illustrates a further modified form of the invention in which the ion pick-up electrode and the anode consist of helical strips interspaced and coiled progressively side by side.

65 Referring to Figures 1 and 2, the anode 1 is cylindrical and is carried by the support 2.

The cathode support 3 maintains the tungsten filament 4 of .06 millimeter diameter at the centre of the anode while the third electrode or grid 5 is symmetrically disposed and retained by the support 6. The dimensions indicated have been found satisfactory in practice but it must be understood that the dimensions of the several parts may be varied as may be found necessary or desirable. This form of construction presents a third electrode surface of very large area which it will be seen is substantially parallel with the adjacent electron stream emitted by the cathode.

The family of static characteristic curves shown in Figure 3 illustrates the variation of anode and grid current with variation of grid voltage with various values of anode voltage, namely, 105, 100, 95, 90 and 85 volts, respectively. While these curves are of interest in giving information concerning the performance of the device in low frequency applications, it must not be assumed that they will hold at radio-frequencies and where it is desired to ascertain the quantitative performance at such frequencies it is essential to make a measurement of the negative impedance at the frequency at which the device is desired to operate. For this purpose a circuit consisting of parallel inductance and capacity with means for adjusting the total effective resistance of the oscillating circuit so formed, may be connected between grid and grid battery or potentiometer or between the grid and the negative filament terminal and the resistance in the tuned circuit varied until oscillations therein are only just sustained. The total effective values of L, C and R with the filament switched off in the tuned circuit, are now ascertained and the value of L/CR may be taken as a measurement of the negative impedance of the device at the tuned frequency. Measurements made in this way give a value at 10^6 cycles, for the device whose characteristics are illustrated, of approximately minus 37300 ohms for the conditions $E_a=105$ volts, $E_f=4.3$ volts, $E_g=0$ volts and it will be noted that this value diverges widely from the figures calculated from the static characteristic.

However, with other adjustment considerably better negative impedance values than the above can be obtained. Thus with $E_a=110$ volts, $E_f=4.9$ volts and $E_g=0$ volts a negative impedance of 18800 ohms was measured at 10^6 cycles.

By careful adjustment, frequencies have been generated of the order 10^7 cycles per second with a device of this type, there being no deliberate retroactive coupling and a condenser of one micro-farad being connected with as short leads as possible between the anode and the negative filament terminal in order to avoid unintentional retroactive effects due to the inductance of the leads of the anode circuit.

Figure 4 shows a series of characteristics for the same device taken with varying filament temperatures and illustrates how the negative input impedance can be varied by adjustment of the filament voltage.

5 In cases where the negative input impedance cannot be made numerically small enough for the particular circuit with which the device is to be used, retroaction may be used between anode and grid circuits in any 10 of the well known ways. Where in order to secure improved amplification or detection it is desired to adjust the device electrically to a point where the negative input impedance 15 is so low that sustained oscillations would be set up, negative or reversed retroaction may be used either to control the amplitude of such oscillation or to suppress it.

20 The closeness of approach to oscillation may be controlled by varying the effective positive resistance of the oscillatory circuit by means for example of a variable condenser in series with a resistance shunted across 25 the oscillatory circuit.

25 In some cases the telephones or other detecting device may be included in the grid circuit in series with the radio frequency circuit and in this case enhanced selectivity to 30 a particular audio-frequency can be obtained by the choice of suitable constants for the telephones and if desired by the use of an adjustable condenser in parallel with them since in this case the negative input impedance 35 of the device will operate to reduce decrement both of the radio-frequency circuit and of the telephone circuit at their appropriate frequencies.

35 In the modification illustrated in Figure 5, 40 advantage is taken of the magnetic field of the filament current and the extended third electrode surface is provided by the arrangement of a series of conical plates or discs 7 carried by the support 8. The dotted line 45 9 in this figure indicates the general direction of motion of an electron towards the anode, while the dotted line 10 indicates the general direction of travel of a positive ion towards the collecting surface of the third electrode 50 or grid. In a modified form the discs may be flat or curved.

55 When magnetic fields are employed to modify the paths of the positive ions and negative charges, these fields may be produced by a coil surrounding the tube and energized from a source external to the envelope. A form of third electrode suitable for use with an axial magnetic field is illustrated in Figures 6 and 11, in which the vanes 60 or blades 11 are curved to conform with the modified paths indicated by lines 9 and 10. Figure 11 also shows the magnetizing coil surrounding the tube to serve as a means for establishing a magnetic field.

65 In some cases, an electrode distinct from

the grid proper is incorporated in the electron discharge device and is arranged and disposed to collect the charges of positive ions for imposing on the grid. This electrode and the grid are electrically associated by being directly connected within or without the envelope, or by any other type of electrical coupling which will serve to impress on the grid, potentials corresponding with the pick-up of positive ions and conduction of the 70 charges thereof by the other electrode.

75 In this modification, therefore, there are two associated electrodes, the one adapted primarily to control the electron flow from cathode to anode and the other primarily to pick up the charges of positive ions. These two associated electrodes may lead to a common terminal as in Figure 7 or to separate terminals as in Figure 12. In the latter case instead of directly connecting the 80 two terminals by an electrical conductor, a potential difference may be impressed thereon or they may be connected respectively in circuits which are inductively coupled together as indicated in Figure 12.

85 In such cases it is generally contemplated to dispose the ion-pick-up electrode or collector out of the electron path between cathode and anode. In one arrangement the ion-pick-up electrode is interspaced with the anode, that is to say, the electrode occupying 90 spaces in the anode, as for example two helical strips coiled progressively side by side as shown in Figure 12. In another arrangement illustrated in Figure 7, the anode 12 consists of a cylindrical coil surrounding the third electrode or grid 13 disposed symmetrically about the cathode 4. The fourth or 95 ion-pick-up electrode 14 consists of a cylinder surrounding the anode. In this case the electrodes 13 and 14 are connected together within the envelope of the discharge device.

100 The diagram of Figure 8, which shows an electron discharge device 15 constructed in accordance with this invention, connected in 105 a radio circuit, is self explanatory.

110 During manufacture the device may be treated as though a hard vacuum were to be obtained by the usual methods for the removal of occluded gases, and subsequently 115 the purified gas, in this case helium, should be admitted to the envelope and adjusted to the desired pressure sufficient to give the tube a pronounced negative resistance characteristic in the grid circuit by the flow of current resulting from the collection of positive ions upon the said large area of the control electrode. The most suitable pressure will vary somewhat according to the purpose for which the device is required and according to the design and proportions of the parts. The pressure may be determined experimentally provided that sufficient precautions are taken to exclude oxygen and other impurities tending to interfere with emission, 120 125 130

by ascertaining the dynamic or static characteristics of the devices while they are connected to the pumping system. It was found that the pressure of a mixture consisting of 5 95% helium and 5% neon of the order of 0.6 millimeter of mercury gave satisfactory results in receiving valves of the dimensions indicated in Figures 1 and 2. It is well known that the number of collisions between electrons and molecules in an electron discharge device depends on the ratio of the distance between cathode and anode and the mean free path of an electron amongst the molecules. Further, it is known that the number 10 of such collisions resulting in ionization of the gas or vapour varies considerably for different media. It follows that the amount of ionization depends largely on the distance between cathode and anode and the pressure 15 and characteristics of the medium and of course the operating voltage. Strong ionization effects are needed in the present device and it is desirable to employ such a pressure that the number of ions being produced is 20 an appreciable percentage of the number of electrons producing them; the presence of too little gas necessitates an unduly high anode voltage in order to obtain satisfactory negative resistance values, or may make it 25 impossible to produce satisfactory values in any circumstances, whereas too much gas makes it impossible to raise the anode voltage high enough to give satisfactory dynamic negative resistance values without producing 30 discontinuities in the characteristic curve. In some cases the valves have to be subjected to a subsequent ageing process, possibly for the removal of traces of impurities. It would appear, however, that if sufficient 35 precaution is taken to exclude impurities, the ageing process may be dispensed with at least in the case of some gases. Where gases which are chemically inert with respect to the filament are used as the media to be 40 ionized, getters may be employed.

The static characteristics shown in Figure 3 of a device constructed according to Figures 1 and 2, and treated as described above, are substantially the same over the 45 ranges shown whichever way the grid voltage is varied, the curves being free from discontinuities and loops. This, in conjunction with the variation in negative resistance input characteristic with different filament heats 50 shown in Figure 4, is of great advantage in the control, for example, of a tuned circuit intended for the reception of telephony, since with suitable values of anode and grid potential—and the latter may be zero, positive 55 or negative to the negative end of the filament—it is possible to give the associated circuit any desired value of decrement from that determined by its positive resistance 60 down to zero.

65 In the case of discharge devices having

negative resistance characteristics in which loops occur it will be appreciated that this smooth control of decrement is not possible in the range covered by the loops and if they are present there is always the danger that 70 an atmospheric or a variation in the battery voltage may cause the apparatus to "flop" around such a loop, necessitating its resetting. Moreover, where such devices are used for the generation of oscillations, it is 75 clear that the amplitude of such oscillations must at least be equal to the voltage width of the loop and that anything causing the amplitude to decrease below this value will cause a cessation of the oscillation. It may 80 further be remarked that where such loops exist, a specially high ratio of L to C is generally necessary for the production of oscillations.

However, loops in the characteristic may 85 not be objectionable if the working part of the characteristic is well removed from them, and if the curve repeats without loops over the working range.

When this invention is to be used for generating oscillations, the mean potential of the grid or ion collecting member may be made considerably more negative than any of those values of grid voltage which give a negative slope to the grid current curve or 90 indeed any grid current at all. In this condition it will, in some cases, be necessary to start the oscillation by means, for example, of an external electrical impulse applied to the inductance of the oscillating circuit. The 95 adjustment of the apparatus in this way with the grid so negative that normally no current flows through the valve, will in many cases give an enhanced efficiency to the device as a generator of oscillations, but in this 100 state the device is not capable of giving the smooth control of decrement from that normal to the circuit down to zero, that it can 105 give when the grid is at or about the same potential as the negative end of the filament. 110

I claim:

1. An electron discharge tube comprising in combination an envelope, an electron emitting cathode, and an anode mounted therein, a control electrode having a relatively large area which can collect positive ions and a relatively small area subject to direct electron bombardment, and a gaseous filling within said envelope, capable of being ionized by collision and at a pressure sufficient to 115 give the tube a pronounced negative resistance characteristic in the grid circuit by the flow of current resulting from the collection of positive ions upon the said large area of the control electrode. 120

2. An electron discharge tube as defined in claim 1 and wherein the gas is at a pressure of a substantial fraction of a millimeter of mercury. 125

3. An electron discharge tube comprising 130

in combination an envelope, an electron emitting cathode, and an anode mounted therein, a control electrode consisting of a plurality of plates located between the cathode and the anode and lying substantially along the 5 electron stream, a gaseous filling within said envelope capable of being ionized by collision and at a pressure under normal operation of the tube to produce substantial 10 ionization of said gas, whereby said plates offer minimum impedance to the electron stream and present a relatively large area for attracting and collecting positive ions from the ionized gas thereby to produce a 15 pronounced negative resistance characteristic in the grid circuit.

4. An electron discharge tube as defined in claim 1 and wherein said gaseous filling consists mainly of helium gas.

5. An electron discharge tube comprising 20 in combination an envelope, a linear electron emitting cathode, means for establishing a magnetic field substantially parallel to said cathode to modify the paths of the electron 25 flow from said cathode, a control electrode consisting of a plurality of plates conforming with the modified electron paths and a gaseous filling capable of being ionized by collision and at a pressure of approximately 0.6 30 millimeter of mercury.
